DESIGN FOR A TABLE SCARF OR SIMILAR ARTICLE

William Emil Rutsch, Teaneck, and Otto Schulze, North Bergen, N. J., assignors to The American Fabrics Company, Bridgeport, Conn., a corporation of Connecticut

Application July 6, 1938, Serial No. 78,291

Term of patent 3½ years

To all whom it may concern:

Be it known that we, William Emil Rutsch and Otto Schulze, respectively citizens of the United States and of the German Reich and respectively residents of Teaneck, in the county of Bergen and State of New Jersey, and of North Bergen, in the county of Hudson and State of New Jersey, have invented a new, original, and ornamental Design for a Table Scarf or Similar Article, of which the following is a specification, reference being had to the accompanying drawing, forming part thereof.

The figure is a plan view of a table scarf,
showing our new design.

The dominant feature of our design consists of contrasting areas arranged on a table scarf as shown.

We claim:

The ornamental design for a table scarf or similar article, substantially as shown and described.
